UNITED STATES PATENT OFFICE.

CHARLES BAKER CRAFTON, OF MASON CITY, ILLINOIS, ASSIGNOR TO OTHO S. KING AND WILLIAM Y. MCLEMORE, OF SAME PLACE.

BEVERAGE-MIXER.

SPECIFICATION forming part of Letters Patent No. 400,547, dated April 2, 1889.

Application filed August 24, 1888. Serial No. 283,617. (No model.)

To all whom it may concern:

Be it known that I, CHARLES BAKER CRAFTON, a citizen of the United States, residing at Mason City, in the county of Mason and State 5 of Illinois, have invented a new and useful Improvement in Beverage-Mixers, of which the following is a specification.

The object of my invention is to provide a simple, cheap, durable, effective, and easily-10 operated milk-shake or lemonade-mixer, and I attain this object by the construction and novel combination of parts, fully set forth hereinafter in connection with the accompanying drawings, and specifically pointed 15 out in the appended claim.

In the drawings, Fig. 1 is a view of the improved shake arranged in the operative position in a glass. Fig. 2 is a vertical sectional view of the same.

20 Referring to the drawings by letter, A designates a cover which is adapted to fit snugly in the top of a glass, and it is provided with a groove, a' , in its overhanging flange a , which receives the upper edge of the glass. In a 25 central bearing, a^2 , in this cover, is mounted the vertical rod or shaft B, which is provided above and below the said bearing with the collars b , which prevent vertical movement of the shaft.

30 C represents a wire which is wound spirally around the vertical rod or shaft above the cover, and D represents a knob or handle mounted on the rod or shaft and adapted to slide vertically thereon. This knob or handle 35 is provided with a central axial bore, d , to receive the rod or shaft, and a communicating spiral groove or channel, d' , to slide on the spiral wire, whereby when the knob or handle is moved vertically the rod or shaft will be 40 rotated. The lower end of the rod or shaft is provided with the radial wings E E, which are adapted, when the former is rotated in the manner described, to agitate the contents of the glass.

It will be seen that the cover is so constructed- 45 as to obviate the danger of the contents of the glass being dashed out during the shaking operation. When operating, hold the cover in place on the glass with one hand and move the knob or handle vertically with the other. 50

The bearing a^2 , above referred to, consists of a vertical barrel, G, which passes through registering central apertures in the cover, and a downwardly-convexed web, I, which is attached to the under side of the cover at its 55 center, the ends of the said barrel being provided with lateral flanges H H to engage the cover and the web. It will be evident that these flanges receive the impact and the wear of the collars b , and therefore protect the 60 cover.

Having described my invention, I claim—

In a beverage-mixer, the combination of the cover having a central aperture, the downwardly-convexed web I, having a central aperture registering with the aperture in the cover, the bearing a^2 , consisting of the vertical barrel G, arranged in the said registering apertures and provided at its upper and lower ends with flanges H H, which bear respectively against the cover and the web, the vertical rod or shaft mounted in the said barrel and provided with collars b , which bear, respectively, against opposite ends of the barrel, a wire, C, being wound spirally on that portion of the rod or shaft above the said collars, the beater-wings secured to the rod or shaft below the collars, and the spirally-bored knob or handle sliding on the spirally-wound wire on the upper portion of the rod or shaft, substantially as specified. 75

In testimony that I claim the foregoing as my own I have hereto affixed my signature in presence of two witnesses.

CHARLES BAKER CRAFTON.
